UNITED STATES PATENT OFFICE.

ROBERT J. SHEEHY, OF NEW YORK, N. Y.

PRINTING-TELEGRAPH.

No. 813,477.

Specification of Letters Patent. Patented April 24, 1906.

Application filed May 22, 1903. Serial No. 158,863.

To all whom it may concern:

Be it known that I, ROBERT J. SHEEHY, a citizen of the United States, residing in the borough of Manhattan, city of New York, county of New York, State of New York, have invented certain new and useful Improvements in Printing-Telegraphs, of which the following is a specification.

My invention relates to that class of printing-telegraphs in which main-line currents control local devices and circuits to effect the printing of desired characters and in which such printing is effected both during those periods when the main line is interrupted as well as when the line is closed, the printing being effected either by a prolongation of the closing of the circuit or a prolongation of the interruption of the circuit.

Heretofore in instruments of this general class it has been customary to place the trailer of the sunflower and its segments in the main-line circuit. Such an organization is objectionable for various reasons and primarily because in operating comparatively long circuits with such strength of current as would be required it is difficult to maintain a proper insulation of the sunflower-segments. The trailer in passing from segment to segment is under such conditions liable to produce sparking, resulting in burning out of the intervening insulators and deterioration of the contacts themselves. Further objection exists in the fact that in such organizations it is impossible to secure any adjustment of the makes and breaks of the main line, since the sunflower-segments are fixed in positive relation to each other and no practical means of varying the relations of the contacts or segments to suit the line conditions is possible. In my improved organization these objections are entirely obviated, as I employ a special interrupter for opening and closing the main line. Such an interrupter may be operated directly from the type-wheel shaft, and its organization may be such as to permit of any desired adjustment of duration of the main-line contact. I am thus enabled to produce an instrument capable of being operated over circuits of any practicable length without exposing the sunflower contact and trailer to any danger of destruction, and should the mechanical interrupter which I employ be injured by sparking or wearing of the parts it may readily be replaced in a

few moments at an insignificant expense. I have found that upon all classes of circuits my improved instrument works with a greater reliability and precision than instruments of the class in which the sunflower is included in the main line. This I attribute to the fact that by means of the interrupter devices I employ I am enabled to secure positive contacts of any desired duration and not only eliminate the sunflower, but also the keyboard from the main-line circuit.

A further feature of my invention consists of a means by which the amount of work to be done by an instrument when receiving is reduced, and this I accomplish by throwing the trailer of the sunflower out of contact with the sunflower-segments, thus relieving the instrument of a fractional load which otherwise it would be obliged to carry when receiving. In printing-telegraph instruments the receiver being controlled or operated from the transmitter there is a small appreciable difference in time of movement between the two instruments, and by relieving the receiver of the fractional load caused by the pressure of the sunflower-trailer the instrument responds more readily to the transmitter, and consequently I obtain greater precision in the conjoint action of the two instruments.

The above primary features of my invention, as well as other novel characteristics thereof, are hereinafter set forth in detail.

In the accompanying drawings I have shown my invention embodied in an organization which I have found by a practical demonstration to be an efficient one and is, in fact, the best embodiment of the invention now known to me. Obviously, however, changes may be made by those skilled in this art without departing from the principle of the invention.

Figure 1 is a diagrammatic view illustrating the general organization and operation of the invention, and Fig. 2 is a detailed view illustrating the type-wheel shaft and parts carried thereby, together with the means for throwing the trailer out of and into engagement with the sunflower.

L indicates the main line, and M B the main battery. The drawings show but one terminal station or instrument. Between it and the distant-terminal instrument other instruments may be introduced into the

main line, as desired. A main battery may also be located at the distant end of the line or at intermediate points, if found desirable.

R represents a neutral relay through which the line is grounded, and a switch s may be placed in the line for the purpose of opening the circuit to break the sending instrument. At a point between the neutral relay and the line coming to the instrument I place the circuit-interrupter. This may consist, as shown, of the plate A, of insulating material, in which the end of the type-wheel shaft may have a bearing. On this shaft is a toothed wheel C, having half as many teeth as there are divisions on the type-wheel. An arm D, carrying an insulated point d, preferably of agate or some similar material, is normally drawn toward the toothed wheel to bring the point into engagement therewith by a spring d', which may be adjustable. This lever carries a contact d², which works against an adjustable contact d³, the contacts being drawn together by the action of the spring d'. The main line is connected with the lever, and consequently with the contact d², and extends thence from the adjustable contact d³, through the switch s and relay R to line or earth. As the type-wheel shaft is rotated, as hereinafter described, the toothed wheel thereon acting upon the agate point of the lever opens and closes the contacts d² and d³.

The armature R' of the relay R, which is provided with an ordinary retractable spring, plays between two adjustable contact-posts r and r'. As shown in Fig. 1, the instrument is in condition for transmission. The main-line circuit is open at the contacts d² and d³. The armature-lever R is therefore against its back contact r, and a local circuit through the battery L B is completed as follows: from one pole of the battery L B to the armature-lever, its stop r, the lever S² of the switch, and by wire 1 of the coils of the differentially-wound print-magnet P M, thence by wire 2 through the coil of an escapement-magnet E to the opposite pole of the battery. The armature of this magnet on one end or side of the T-shaped escapement-lever F is attracted, and one of the escapement-pallets f is thrown into position to engage one of the teeth of the toothed wheel G, fast on the power-driven type-wheel shaft and having half as many teeth as there are divisions in the type-wheel. It will be noted that in this position of the apparatus the point d of the mechanical circuit-interrupter is about just resting on the point of one of the teeth of the wheel C. Assuming, therefore, that none of the keys is depressed, the type-wheel shaft will be moved by its power until the teeth of the wheel G comes against the point of the escapement-pallet just mentioned, and the shaft is rotated a sufficient distance to permit the point d on the lever of the circuit-interrupter to enter between two of

the teeth of the wheel C and complete the main-line circuit at the contacts d² and d³. On this completion of the circuit the relay R is energized, its armature is attracted, and a circuit from the local battery L B is completed from the armature-lever R' and its stop r', the arm S³ of the switch and by wire 3 through the other coil of the print-magnet, thence by wire 4 through the coil of the escapement-magnet E' to the opposite pole of the battery. This magnet attracts its armature on the escapement-lever, and the lever is thrown in the opposite direction, and the operation above described is repeated, except that the movement of the wheel G and of the type-wheel shaft to bring the tooth of the wheel against the escapement-pallet f' causes the wheel C to lift the lever D, and the main-line circuit is interrupted. This operation being repeated indefinitely, the type-wheel shaft rotates with a regular uniform motion. If, however, one of the keys K K' K'', &c., should be depressed, the type-wheel shaft would be arrested either with the main-line circuit open or closed at the contacts d² and d³, as the case may be. In the drawings one of the keys K is shown depressed. The trailer of the sunflower is in contact with the segment thereof corresponding with the depressed key, and a local circuit is completed from the battery L B through wire 5, contacts of key K, wire 6, sunflower-segment and trailer, and coil of arrester-magnet H to the opposite pole of the battery. The armature-lever H' of this magnet is attracted and its end h is thrown into engagement with a toothed arresting-wheel I on the type-wheel shaft, and which has as many teeth as there are divisions on the type-wheel. The shaft is therefore arrested with the escapement-wheel G and the circuit-interrupter wheel C substantially in the positions indicated. The open condition of the main circuit is therefore prolonged during the time that the type-wheel shaft is arrested by the depression of the key K. The current from the battery L B has therefore time to fully charge or energize the print-magnet P M. Its armature-lever T is attracted and the platen T' is thrown up against the type-wheel. Of course any suitable construction of print-lever, platen, paper-feeding device, &c., may be employed. When the key K is raised, the armature of the arresting-magnet is by its spring thrown out of engagement with the wheel I and the step-by-step rotation of the type-wheel shaft is resumed until another key is depressed, the type-wheel arrested, and the impression taken in the manner described.

When the instrument is to be arranged for receiving, the gang-switch S² S³ is thrown to the left. This changes the connections of the local battery and reverses the order in which the two escapement-pallets engage the

teeth of the wheel G, so that the instrument is then held by the pallets in coincident relation with the transmitter. At the same time, the circuit-interrupter of the receiving-instrument should be thrown out of action, and this may be done, as shown, by means of a switch s' closing a shunt-circuit around the interrupter. The switch s' may be a part of the gang-switch $S^2 S^3$. The cross-bar of the gang-switch is connected with a pivoted lever O, the opposite end of which is pivoted to a rod O', connected at its end with a flexible or hinged arm, but preferably an elastic arm O². This arm lies in an annular groove in a sleeve O³ on the type-wheel shaft and carrying the trailer of the sunflower. The sleeve is slotted for the reception of a pin on the shaft, so that an endwise motion may be imparted thereto. When the gang-switch is thrown to the left to adapt the instrument for the reception, the arm O² draws the trailer out of engagement with the sunflower. In order to permit of an adjustment of these parts so as to produce the proper contact-pressure between the trailer and the segments, the end of the rod O' is screw-threaded and passes through the spring-arm O³, there being a clamp-nut on each side thereof.

In Fig. 2, P indicates the pinion through which the type-wheel shaft is driven by a clock-train or any othersuitable power. The pinion is preferably mounted on a sleeve, connected by a spiral spring enveloping the shaft with a collar adjustably mounted on the shaft, the construction being ordinary and well understood. The arresting-wheel I is mounted upon a hub enveloping the shaft and provided with a set-screw to rigidly attach it to the shaft. The escapement-wheel G is similarly mounted.

When the arrangement for disengaging the trailer from the sunflower segments is not adopted, it is desirable to employ a switch Q for opening the local circuit of the keyboard-contacts when the instrument is receiving.

Of course it is obvious that the idea of reducing the load on the receiver by throwing the trailer out of contact with the sunflower is applicable to other forms of printing-tele-

graphs.

Obviously instead of using a straight current and neutral relays the circuit-interrupter may be a pole-changer and reverse currents sent to line, in which event polarized relays would be employed. This may be done by providing another lever D to be operated by the wheel C and suitable electrical connections, which would be found advantageous in duplexing or quadruplexing the instruments.

Any suitable ordinary unison devices may be employed.

I claim as my invention—

1. In a printing-telegraph, the combination of the type-wheel and shaft, a main-line battery, a circuit-interrupter included in the main line, and actuated by the shaft to change the condition of the line-circuit at each step or movement of the type-wheel, the main-line relay, two local circuits controlled at the front and back stops of its armature-lever, a local battery for said circuits, a double-wound print-magnet having a coil in each local circuit, a magnet in each local circuit for effecting a movement of the type-wheel each time the condition of the circuit of the line is changed, the keys and their local circuits including the sunflower segments and trailer, and an arresting-magnet common to all the key-circuits for arresting the type-wheel when a key is depressed and thereby prolonging the then open or closed condition of the line-circuit, whereby the print-magnet is charged by the prolonged closing of the local circuit and an impression from the type-wheel effected, substantially as set forth.

2. In a printing-telegraph, the combination of the type-wheel, its shaft, a main-line battery, a main-line circuit-interrupter actuated by the wheel or shaft, the line-relay, the local battery, two circuits therefrom controlled at the front and back stops of the relay and each including a coil of a print-magnet and an escapement magnet, the escapement-wheel and lever, the keys, their local circuits including the sunflower segments and trailer, the arresting-magnet common to all the key-circuits, its armature-lever, and the arresting-wheel on the type-wheel shaft, substantially as set forth.

3. In a printing-telegraph, the combination of the sunflower, its trailer and means for disengaging the trailer from the sunflower when receiving.

4. In a printing-telegraph, the combination of the sunflower, its trailer, a switch for connecting the instrument for either transmission or reception, and devices operated by the switch when moved into position for reception to disengage the trailer from the sunflower.

5. The combination of two printing-telegraph instruments connected by a line and one arranged for transmission to the other, the trailer of the transmitter bearing on the sunflower, and the trailer of the receiver being thrown out of contact with its sunflower.

In testimony whereof I have hereunto subscribed my name.

ROBERT J. SHEEHY.
